UNITED STATES PATENT OFFICE.

JAMES H. GRAHAM, OF TORRINGTON, CONNECTICUT, ASSIGNOR TO THE STANDARD COMPANY, OF TORRINGTON, CONNECTICUT, A CORPORATION OF MAINE.

SAFETY SET-SCREW.

1,082,945.

Specification of Letters Patent.

Patented Dec. 30, 1913.

Application filed May 24, 1911. Serial No. 629,226.

To all whom it may concern:

Be it known that I, JAMES H. GRAHAM, a citizen of the United States, residing at Torrington, in the county of Litchfield, State 5 of Connecticut, have invented certain new and useful Improvements in Safety Set-Screws, of which the following is a description, reference being had to the accompanying drawing and to the letters and figures 10 of reference marked thereon.

My invention relates to improvements in so-called safety set screws, which are embedded screws used for example to hold collars and pulleys on shafts and the like, leaving 15 no projection and allowing convenient removal whenever it is desired to do so.

The invention is in a sense designed as an improvement on the safety set screw shown in Patent No. 869,086, issued October 22d, 20 1907, to Clémence E. Hoffman, and consists of novel features and combinations of the same, all as hereinafter described and referred to in the appended claim.

The invention is illustrated in the accompanying drawings, in which,—

Figure 1 is a sectional side elevation of my invention as applied for fastening a collar on a shaft; Fig. 2 is a sectional view of the set screw showing three different forms 30 of the point, viz., cupped, flat and oval; Fig. 3 is a detail view of the wrench; and Fig. 4 is a sectional view like Fig. 1, showing the wrench applied to the safety set screw.

In these drawings, the safety set screw 35 itself is illustrated by 1. It has an external screw thread 2, and is formed with a socket having two internal screw threads running in opposite directions. While the set screw may have a longitudinal opening extending 40 entirely through it instead of the socket, the latter form is preferable, and the lower end of said socket, or end adjacent where the end of the wrench comes, is cupped, as shown at 3, in effect forming a shoulder or seat 4, so 45 that only a minimum frictional contact of

the inner end of the wrench with the inner end of the socket takes place, thus preventing interlocking of the wrench with the set screw. By this arrangement, no matter how great a strain is applied to the wrench 50 to manipulate the safety set screw in or out, very slight pressure only is necessary to release the wrench from the screw. The wrench is illustrated by 4', and comprises the squared central portion 5, adapted for 55 the ready attachment of a wrench or other tool, its end portions 6 being threaded reversely to each other and of a pitch corresponding to the pitch of the internal screw threads of the socket, which pitch is greater 60 than that of the external thread 2. The outer ends of the wrench are rounded, as shown at 7, so as to minimize the frictional engagement of the ends of the wrench with the seat in the socket. 65

Having thus described my invention, what I claim as new and desire to secure by Letters Patent, is:

The combination of a safety set screw provided with an external screw thread and a 70 socket having right and left hand screw threads of greater pitch than the external screw thread and having a seat at the lower end closing said socket and forming a bearing end for the set screw, and a wrench having a central portion for engagement of a 75 tool and having oppositely extending portions with right and left hand threads, respectively, for engagement with the internal screw threads of the socket, said extending 80 portions being of sufficient length to permit the ends thereof to engage the closed end of the socket.

In testimony whereof I affix my signature, in presence of two witnesses.

JAMES H. GRAHAM.
